FLOATING DECK HAVING REINFORCED
ANNULAR GAS SPACE

Frank A. Howard and Charles H. Haupt, Elizabeth, N. J., assignors to Standard Oil Development Company, a corporation of Delaware

Application July 11, 1933, Serial No. 679,859

6 Claims. (Cl. 220—26)

This invention relates to improvements in floating decks for oil tanks or the like.

The invention will be fully understood from the following description taken in connection with the accompanying drawings in which latter—

5 Fig. 1 is a transverse sectional view through a tank with a modified form of floating deck disposed in position upon the liquid within the tank;

Fig. 2 is a bottom plan view of the structure of Fig. 1;

10 Fig. 3 is a transverse sectional view taken along the line V—V of Fig. 2;

Fig. 4 is a transverse sectional view through a tank with still another modified form of floating deck disposed in position upon the liquid within 15 the tank; and

Fig. 5 is a bottom plan view of the structure shown in Fig. 4.

Referring to Figs. 1, 2 and 3 of the drawings, reference numeral 1 designates an annular tank 20 adapted to contain oil or other combustible material 2. The liquid 2 in this tank supports a floating roof which is constructed of a circular flanged deck 18, the under surface of which slopes upwardly from the center of the deck to the periphery of the flange 30.

25 A suitable annular sealing means 15 projects from the upper portion of the roof into sealing engagement with the side walls of the tank 1. An apron 19 depends from the periphery of the flange 30 substantially parallel 30 with the side walls of the tank to form an annular space with the sloping under surface of the roof. A plurality of equally spaced triangular plates 24 are secured to the under surface of the roof from an intermediate point 21 to the periphery 35 and extend therefrom radially outward and downward to engagement with the apron 19 to which they are also secured and divide the annular space into a plurality of downwardly extending non-communicating compartments when

40 the roof is partially submerged. These compartments, as shown, may be converted into pontoons or into alternate gas storage spaces 26 and pontoon compartments 27 by means of an annular under-plate 28, secured to the under surface of 45 the roof at an intermediate point 21 and to the lower edge of the apron 19. With the under-plate in place, it cooperates with the under surface of the deck portion 18 to form annular gas

50 space 23 beneath the intermediate portion of the roof. Preferably, the under-plate is provided with perforations at spaced compartments 26 to admit vapors thereto from the annular gas space 23. Alternately, sections of the under-plate may 55 be omitted at spaced compartments, and some of

the advantages of the invention will be retained.

According to this particular form of construction, the roof in effect consists of a substantially self-supporting central deck portion 18, which is of smaller diameter than the tank, and a self-supporting hollow wedge-shaped annular rim portion for the deck formed by the flange 30, the apron 19, and the under-plate 20, and having internal partitions 24 dividing the space into a plurality of separate compartments of which certain ones are provided with communicating openings to the liquid and vapor beneath the roof. In a roof of this type the spaced gas compartments 26 and air compartments 27 prevent the uninterrupted flow of gas about the periphery of the roof, and the accumulation of gas at any one point should the roof assume an inclined position upon the liquid, due to any temporary concentration of weight at any point. A suitable drain 29 is provided at the central portion of the deck to permit of draining water or the like accumulating upon the upper surface of the deck.

Referring to Figs. 4 and 5, a similar form of floating roof is shown which is constructed of a sectional large circular deck the under surface of a portion 32 of which slopes gradually upwardly and outwardly to a portion 33 which slopes sharply upwardly and outwardly to the periphery of the deck. The portion 33 of the deck constitutes an outwardly and upwardly extending flange which extends entirely around the edge of the deck and which is provided with a depending portion 34 which depends below the portion 32 of the deck. An apron 35 depends from the periphery of the portion 33 of the deck substantially parallel with the side walls of the tank and terminates on a level with the depending flange 34. The apron 35 cooperates with the portion 33 and annular flange 34 of the deck to form an annular space around the periphery of the roof. Flanged triangular plates 37 constitute partitions which extend transversely of the annular gas space to divide the annular gas space into separate pockets or compartments. Underplates 38 close the space between the apron 35 and the flange 34 of alternate compartments 39 to form air-tight compartments which function as pontoons. Perforated plates 40 extend between the apron 35 and the flange 34 of spaced compartments 41 to permit of flow of gas from beneath the roof into the compartments 41. The floating roof has a float capacity equal to its total weight. The triangular partitions are sufficiently strong to hold the total weight of the roof if the roof should be hung on one side. A concrete load 43 is disposed

in the center of the roof. A drain 44 is provided leading from the center of the roof.

Various changes may be made within the scope of the appended claims in which it is desired to 5 claim all novelty inherent in the invention as broadly as the prior art permits.

We claim:

1. A floatable roof for tanks, comprising a deck, the under surface of which slopes upwardly to the 10 periphery of the deck, an apron depending from the periphery of the deck to form an annular space with the sloping surface, a plurality of plates secured substantially radially to the sloping under surface and apron to divide the annular space transversely into downwardly opening 15 pockets, and closures covering spaced pockets to form pontoons whereby a balanced arrangement of pontoons and downwardly opening pockets is obtained.
2. A floatable roof for tanks, comprising a deck, the under surface of which slopes upwardly to the periphery of the deck, an apron depending from the periphery of the deck, an annular under plate sloping downwardly and outwardly from an intermediate portion of the undersurface to the apron 20 to form an annular air space, a plurality of substantially radially extending plates dividing the air space into separate compartments, the under plate being perforated at spaced compartments 25 to admit vapors to the compartments.
3. A floatable roof for tanks comprising a substantially self-supporting central liquid displacement portion in the form of an inverted cone, and a self-supporting annular liquid displacement 30 portion comprising a hollow wedge-shaped rim

for the central portion so positioned as to create an annular downwardly opening vapor space between the rim and the central portion, said rim portion having a plurality of interiorly located transverse partitions, dividing it into a plurality 5 of chambers of which alternate chambers are in direct communication with the liquid in the tank and with the annular downwardly opening vapor space between the rim and central portions of the roof.

4. A floatable roof for tanks comprising a substantially self-supporting central liquid displacement portion in the form of an inverted cone and a self-supporting annular liquid displacement 15 portion comprising a hollow annular rim for the central portion to which it is secured so as to create a downwardly opening annular vapor space between the rim and central portion, said rim portion having a plurality of interiorly located transverse partitions dividing it into a plurality of 20 chambers, the annular vapor space and alternate chambers in the rim communicating directly with the liquid in the tank and adapted to receive vapors therefrom.

5. A floatable roof for tanks according to claim 25 4 in which the annular rim is triangular in cross section and is secured to the central portion at a point corresponding to the apex of the triangle.

6. A floatable roof for tanks according to claim 4 in which the annular rim is right-triangular in cross section and is secured to the central portion 30 at a point intermediate the side corresponding to the hypotenuse of the right triangle.
